UNITED STATES PATENT OFFICE.

JAMES SCARLETT, OF SEATTLE, WASHINGTON.

LIFE-SAVING DEVICE.

1,075,122.

Specification of Letters Patent.

Patented Oct. 7, 1913.

Application filed March 20, 1913. Serial No. 755,740.

To all whom it may concern:

Be it known that I, JAMES SCARLETT, a citizen of the United States, residing at Seattle, in the county of King and State 5 of Washington, have invented certain new and useful Improvements in Life-Saving Devices; and I do hereby declare the following to be a full, clear, and exact description of the invention, such as will enable 10 others skilled in the art to which it appertains to make and use the same.

This invention relates to life saving suits of the type which can be slipped over a person fully dressed and an object of the invention is to provide a life saving suit with 15 an interior of wool or other warming material.

A further object of the invention is to provide a suit which will be heavier in the leg 20 portions than in the neck portions.

A still further object of the invention is to provide an air bag held in the interior of the life saving suit, and in providing means for holding the air bag in place, 25 said means serving also to protect the air bag from the heat of the intending user.

A still further object of the invention is to provide a life saving suit with a flexible neck portion, the neck portion being provided with a strip of transparent material. 30

With these and other objects in view the invention comprises certain novel constructions, combinations, and arrangements of parts as hereinafter more fully described 35 and claimed.

In the drawings, where corresponding parts are designated by similar reference characters: Figure 1 is a view of a diver wearing the suit forming the subject-matter 40 of the present matter, the suit being shown in section, Fig. 2 is an elevation of the suit showing parts thereof in section, Fig. 3 is a detail section showing the valve connections for the air bag.

There have been put on the market a 45 number of life saving devices which are effective in keeping the user afloat, but inasmuch as the body is brought in intimate contact with the water, which is frequently 50 very cold, the person using the life saver contracts sickness due to the exposure, which frequently results in death.

It is the purpose of the present invention to provide an air supported water tight suit

lined with wool or other warm material 55 which will be effective in retaining the animal heat of the user.

Referring to the drawings, the suit as a whole is designated as 1, the suit having a flexible neck portion 2 provided with a cord 60 or other securing means 3 for the purpose of drawing the upper end of the neck portion together to prevent ingress of water. The portion 2 is also provided with a transparent strip 4, which may be of glass, but 65 preferably celluloid or xylonite. The body is provided with arms 5 which may be made of the same material of which the neck portion is made. The central portion of the body is made somewhat heavier than the 70 neck portions while the leg portions are made still heavier so that the thickness or weight of the material of which the suit is constructed increases from the neck portion to the leg portions. For the purpose of 75 sustaining the body there is provided an air bag 6, loosely mounted within the body portion 1, and held in place by means of a flap 7 and straps 8, the flap 7 being designed to be secured to the back of the suit, as shown 80 in Fig. 2, and is provided with suitable openings 9 for engaging buttons or other securing means 10. The object in placing the flap 7 in the back of the suit is to prevent the feet of the intending user from coming 85 in direct contact with the air bag 6. Secured to the sides and front portion of the suit are the straps 8, which straps are provided with openings for engaging buttons or other securing means 11 secured to the suit. 90 The air bag 6 is made in one cylindrical piece and has its end portions provided with interlocking means, buckles 12 being shown in the drawings for this purpose. For the purpose of inflating the air bag 6 there is 95 provided a tube 13 provided with a check valve 14 and an exhaust valve 15, this check and exhaust valve being of the usual construction, as shown in Fig. 3. The whole interior of the body portion and arm and leg 100 portions is provided with a lining of wool or other suitable warming or heat retaining material.

In the use of the suit, the air bag is first inflated and then the suit is drawn on over 105 the clothes of the intending user. After the suit has been completely drawn on the cord or other drawing means 3 may be

drawn taut for the purpose of closing the top of the neck portions 2, or the user may grasp the free end of the neck portion with his hand to prevent the inflow of water. 5 He will then either be let into the water or jump in and keep the neck portion 2 bound tightly until he arises to the surface of the water, after which he may draw the neck portion down from over his head and bind 10 the same as tightly as comfortable around his neck to prevent ingress of water, by means of the cord 3. It will be seen that the air bag 6 completely encircles the body of the user, and that for this reason there 15 is an air space between the upper part of the body portion and the user sufficient to contain air for sustaining life a short time under water, so that if by any accident the person using the suit should come up under 20 a vessel after jumping into the water, he will be able to look out of the transparent closure 4 and free himself from the bottom of the vessel or other wreckage, the air in- closed within the suit being sufficient to 25 sustain life while the user is freeing himself. Insomuch as the arm and neck portions are made of flexible material the occu- 30 pant of the suit will be able to move about freely in the water. Insomuch as the leg portions of the suit are made of heavier and thicker material than the upper portions there will be a natural tendency for the suit to assume an upright position in the water.

What I claim is:—

- 35 1. A life saving suit of increasing thickness from the top to the bottom thereof, and a floating device in the upper part of said suit adapted to space part of the suit from the body of the wearer. 40 2. A life saving suit comprising a floating device carried within the suit, means for holding said device to the suit, and a flexible member hinged to the suit from the interior thereof adapted to cover a portion 45 of said floating device. 3. A life saving suit comprising a floating device carried within the suit, means for securing said floating device to the suit, and auxiliary means for supporting said 50 floating device, said auxiliary means comprising a flap hinged to the interior of the suit and adapted to cover a portion of said floating device. 4. A life saving suit comprising a float- 55 ing device carried within the suit, means for supporting said floating device, a flap hinged to the inside of the back of said suit, and means formed on the flap adapted to engage a portion of the suit to hold said 60 flap around the floating device.

In testimony whereof I affix my signature in presence of two witnesses.

JAMES SCARLETT.
